UNITED STATES PATENT OFFICE.

HERBERT W. CHENEY, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

POTENTIAL STARTER ATTACHMENT.

No. 909,367.

Specification of Letters Patent.

Patented Jan. 12, 1909.

Application filed September 29, 1906. Serial No. 836,757.

To all whom it may concern:

Be it known that I, HERBERT W. CHENEY, a citizen of the United States, residing at Norwood, in the county of Hamilton and 5 State of Ohio, have invented certain new and useful Improvements in Potential Starter Attachments, of which the following is a full, clear, and exact specification.

My invention relates to operating means 10 for starting devices for electric motors.

In operating starting devices for some types of motors, especially in potential starters for induction motors, it is often undesirable that the starter be moved backwards from a "running" to a "starting" position. To this end controllers have been designed which move directly from the "running" position to the "off" position without passing through a "starting" position. 15 However, in order to prevent a careless or inexperienced operator from moving the controller from a "running" to a "starting" position, or from an "off" position directly to a "running" position, some preventive device 20 is necessary, and it is the object of my present invention to provide such a preventive device which shall be both simple in construction and accurate in operation.

Other objects of my invention will appear 25 hereinafter.

To this end my invention in one of its aspects comprises the combination of a controller, a handle therefor, a latch mounted on said handle, and a fixed plate coacting with 30 said latch to prevent backward movement of the handle into certain positions.

In a somewhat different aspect my invention comprises the combination of a rotatable drum, operating means therefor, a pawl 40 coöperating with a notched plate to prevent backward movement of the controller for certain positions, said pawl being manually movable independently of the controller.

Other features of my invention will appear 45 from the following description and claims taken in connection with the accompanying drawings.

Figure 1 is a partial sectional elevation of the upper part of a controller embodying one 50 form of my invention. Fig. 2 is a view similar to Fig. 1 but showing the pawl in another position. Fig. 3 is a partial plan view of the controller of Fig. 1 with the operating handle

removed. Fig. 4 is a development of the notched ring of the controller of Fig. 1. 55 Fig. 5 is a partly sectional side elevation of a controller embodying another form of my invention. Fig. 6 is a partial front elevation of the controller of Fig. 5. Fig. 7 is an enlarged side elevation, partly in section, of the 60 controller operating means; and Fig. 8 is a development of the notched ring shown in Fig. 7.

Referring first to the modification shown in Figs. 1 to 4 inclusive, 10 is the controller 65 casing surmounted by a cap plate 11. Within the casing 10 may be a controller drum of any desired construction, though the operating mechanism here shown is especially designed for a controller drum having duplicate halves which each co-act with one of the two sets of contact fingers during one complete operation of the controller, and with the other set during the next complete operation thereof. Such a controller has 70 duplicate "off", "starting" and "running" positions as indicated in Fig. 3. The controller here shown passes through two "starting" positions between the "off" and the "running" positions, though any desired number of "starting" positions may be used. In the arrangement shown analogous 75 positions are 180° apart. The particular construction and arrangement of the controller drum, however, forms no part of my 80 present invention, which is equally applicable to controllers having but one "off" and one "running" position with any desired number of "starting" positions between them. 90

Extending upwardly from the cap plate 11 and preferably integral therewith is a ring plate 12 having pairs of notches 13 and 13^a, 14 and 14^a, 15 and 15^a and 16 and 16^a, which correspond to the "off", "first starting", 95 "second starting" and "running" positions respectively of the controller. The controller drum is mounted on a shaft 17, on the upper end of which fits the operating handle 18, movable by a knob 19 at its outer end. 100 Pivoted beneath the handle 18 is pawl 20, the inner end of which is normally pressed downwardly by a spring 21 into engagement with the upper surface of the ring 12. The inner end of pawl 20, however, may be lifted 105 by means of a push-button 22 in the knob

19, said push-button having a downward extension 23 which normally engages the outer end of the pawl 20. If desired there may be a spring 24 which normally holds the push-button 22 in its uppermost position.

The ring 12 is constructed so that between certain of the notches, as between 15 and 16, 16 and 13^a, 15^a and 16^a, and 16^a and 13, ratchet teeth are formed, while the surfaces 10 between the remaining notches are flat; that is, all of the notches have that side toward the next position in a forward or clockwise direction of a certain height and the notches 14, 15, and 14^a and 15^a have 15 both sides of such height, while the notches 13, 16, 13^a and 16^a have the side towards the next position in a backward or anti-clockwise direction of a greater height.

When the controller is in any operative position the spring 21 normally holds the pawl 20 in engagement with one of the notches 13 to 16^a. By depressing the push-button 22 the inner end of pawl 20 may be raised, as shown in full lines in Fig. 2, to clear both 25 sides of the notches 14, 15, 14^a and 15^a, and the forward side of the notches 13, 16, 13^a and 16^a. The shoulder 25 within the knob 19 prevents too great a downward movement of the push-button. Although the 30 pawl cannot be raised by the push-button to clear the high side of the notches 13, 16, 13^a and 16^a, a forward movement of the controller causes the pawl to be so raised, as shown in dotted lines in Fig. 2, by the cam 35 action of the inclined surfaces approaching the notches 13, 16, 13^a and 16^a, thus allowing the handle to be moved between certain notches in a forward or clockwise direction while preventing it in a backward or anti- 40 clockwise direction. The push-button 22 being released as soon as a movement of rotation has begun, the pawl 20 drops upon the ring 12, and upon reaching the next notch drops into it, thus interrupting the 45 forward movement and accentuating and accurately determining the controller positions, as well as preventing backward movement of the controller from the "off" and "running" positions. From any "starting" 50 position the controller may be moved in either direction, for it is sometimes desirable that the controller be moved from "starting" position directly to the "off" position without passing through the "running" 55 position. This is permissible because both sides of the "starting" notches are low enough to allow the push-button 22 to raise the pawl 20 to clear them.

In Fig. 5 I have shown at 30 a cast metal 60 supporting frame on which is mounted a sheet metal cover 31. This frame and cover form a casing which may inclose the transformer or transformers (not shown) of a potential starter. Suspended on the lower 65 part of the frame 30 is an oil tank 32 adapted

to contain oil which will surround the controller drum shown at 33. This drum is mounted in downwardly extending arms or projections 34 on the frame 30. The drum 33 is driven through gears 37 and 38 from 70 an operating shaft 36, loosely mounted in a bearing 39 also integral with the frame 30. Mounted on the outer end of the shaft 36 is an operating handle 35, which, as shown in Fig. 6, is secured at its center to the shaft 75 and is provided with two hand grips. The distance between the gear 37 and the handle 35 is slightly greater than the length of the bearing 39 so that there can be a slight loose play or lateral movement of the gear 37, 80 shaft 36 and handle 35. A spring 40 normally maintains the said parts in their innermost position from which they can be moved outwardly by pulling out the handle 35 until the gear 37, spring 40 and bearing 85 39 are all in contact.

Integral with the frame 30 and surrounding the shaft 36 and bearing 39 is a ring 41. This ring is provided with three pairs of notches 42 and 42^a, 43 and 43^a, and 44 and 90 44^a, the notches of each pair being located diametrically opposite each other. These pairs of notches are adapted to be engaged by a sliding pawl or plunger 45, pressed by a spring 49 into engagement therewith. The 95 plunger 45 is mounted in an extension 46 from handle 35. This extension also serves as a pointer to indicate the position of the controller, there being another extension 47 which also serves as a pointer although it 100 does not necessarily contain a spring-pressed plunger. The three pairs of notches above referred to indicate respectively the "off", "starting", and "running" positions of the controller, there being shown in this 105 modification but one "starting" position between the "off" and the "running" positions, instead of two as shown in Fig. 1. The surfaces between the "off" and "starting" positions are flat, while those between 110 the "starting" and "running" positions, and the "running" and "off" positions are inclined to form ratchet teeth as in Fig. 1. By pulling out the handle 35, the plunger 45, the movement of which toward the ring 115 41 is limited by a pin 48, may be lifted clear of the low sides of the "off" and "running" notches and of both sides of the "starting" notches, but cannot be lifted high enough to clear the high sides of the "off" and 120 "running" notches 42, 44, 42^a and 44^a. However, by means of the inclined surfaces which approach these notches a forward movement of the controller raises the plunger 45 over these high sides and allows it 125 to drop into the notches.

The operation of the arrangement here described is much the same as that of Fig. 1, save that instead of depressing a push-button, the handle 35 is moved bodily out- 130

ward when passing from one position to another, while the notches serve to accentuate the controller positions and to limit the direction of rotation from the "off" 5 and the "running" positions to one direction of rotation.

Many modifications of the precise arrangement here shown and described may be made without departing from the spirit 10 and scope of my invention, and in the following claims I aim to cover my invention broadly.

What I claim as new is:—

1. In combination, a controller, a handle 15 therefor, a latch mounted on said handle, and a fixed plate co-acting with said latch to prevent backward movement of the handle into certain positions.

2. In combination, a controller, a handle 20 therefor, a spring-pressed pawl in said handle, and a notched plate with which said pawl co-operates to accentuate predetermined positions of the controller, certain of the notches of said plate being so constructed as to prevent backward movement 25 of the handle therefrom.

3. In a controller, a rotatable drum, a spring-pressed pawl movable with said drum, a fixed notched plate with which 30 said pawl co-operates to determine the controller positions, and means for lifting said pawl out of all of the notches of said notched plate for forward movement of the controller but out of less than all of them for backward 35 movement thereof.

4. In a controller, the combination with a rotatable contact-carrying member and an operating handle therefor, of a fixed notched plate co-acting with a spring-pressed pawl 40 in the handle to determine the controller positions, notches of said notched plate being constructed to limit the motion of said contact-carrying member from the positions corresponding to said notches to one direction 45 of rotation.

5. In a controller, the combination with a rotatable drum and an operating handle therefor, of an interlocking device for permitting rotation of said drum in one direction 50 from all positions and for preventing rotation of said drum in the other direction from certain predetermined positions, comprising a fixed notched ring and a pawl movable with the drum and normally held 55 in engagement with said ring.

6. In a controller, a rotatable drum, an operating handle therefor, a fixed notched ring and a pawl co-operating with said notched ring and normally in engagement 60 therewith, said pawl being manually movable out of engagement with all of the notches of said ring for forward movement of the controller but out of engagement with only some of them for backward movement 65 thereof.

7. In a controller, fixed contacts, a rotatable member carrying movable contacts, an operating handle for the latter, a fixed notched ring, and a manually-movable pawl normally engaging said notched ring, some 70 of the notches of said ring having one side higher than the other for preventing backward movement of the handle therefrom.

8. In a controller, a rotatable drum co-acting with fixed contacts, an operating handle for said drum, and a manually-movable spring-pressed pawl in said handle which co-acts with a notched ring, the surfaces between some of the notches of said ring forming ratchet teeth over which the pawl cannot 80 be raised to allow backward movement of the controller.

9. The combination with a controller having predetermined "starting" and "running" positions, of an operating handle for 85 said controller, and a spring-pressed pawl in said handle co-operating with a fixed notched plate to limit the movement of said controller to a single direction of rotation from its "running" position. 90

10. The combination with a controller which has predetermined "off", "starting" and "running" positions, of an operating handle for said controller, and a manually-movable spring-pressed pawl in said handle 95 which co-acts with a fixed notched plate to limit the movement of said controller to one direction from the "off" and "running" positions while allowing an indefinitely progressive movement in said direction. 100

11. The combination with a controller which has predetermined "off", "starting", and "running" positions, of an operating handle for said controller, and a manually- 105 movable spring-pressed pawl in said handle which co-acts with a fixed notched plate to limit the movement of said controller to one direction from the "off" and "running" positions while allowing an indefinitely progressive movement in said direction and movement in either direction from the other positions. 110

12. The combination with a controller which has predetermined "off", "starting" and "running" positions, of an operating handle for said controller, and a manually-movable spring-pressed pawl in said handle which co-acts with a fixed notched plate to limit the movement of said controller to one 115 direction from the "off" and "running" positions while allowing movement in either direction from the "starting" position or positions. 120

13. In a controller, a rotatable drum, and 125 a pawl co-operating with a notched plate to determine the controller positions, said pawl being manually movable independently of the drum, and certain of the notches of said notched plate being so formed that the pawl 130

- can be independently moved to clear only one of their sides.
14. In a controller, a rotatable drum, a spring-pressed pawl movable therewith, and a notched plate with which said pawl coöperates, said pawl being manually movable independently of the controller, and certain of the notches of said notched plates having one side only of such height that the pawl 10 can be raised to clear it while the other notches have both sides of such height.
15. In a controller, a rotatable drum, an operating handle therefor, and a spring-pressed pawl movable with said drum, and coöperating with a fixed plate having ratchet teeth for preventing backward movement of the controller from certain positions.
16. In a controller, a rotatable drum, operating means therefor, and a pawl coöperating with a notched plate to prevent backward movement of the controller from certain positions, said pawl being manually movable independently of the drum.
17. The combination with a controller 25 having "off", "starting" and "running" positions, of a spring-pressed pawl manually movable independently of the controller and coöperating with a notched ring to prevent movement of the controller directly from the "running" to a "starting" position.
18. The combination with a controller having "off", "starting" and "running" positions, of a spring-pressed pawl manually movable independently of the controller and coöperating with a notched ring to prevent movement of the controller directly from the "off" to the "running" position.
19. The combination with a controller having "off", "starting" and "running" 40 positions, of a spring-pressed pawl manually movable independently of the controller and coöperating with a notched ring to prevent movement of the controller directly from the "running" to a "starting" position, or from the "off" to the "running" position.
20. The combination with a controller having "off", "starting" and "running" 45 positions, of a spring-pressed pawl manually movable independently of the controller and coöperating with a notched ring to prevent backward movement of the controller from its "off" position.
21. The combination with a controller having "off", "starting" and "running" 50 positions, of a spring-pressed pawl manually movable independently of the controller and coöperating with a notched ring to prevent
- backward movement of the controller from the "running" position.
22. In combination, a controller having "off", "starting" and "running" 60 positions, and a spring-pressed pawl manually movable independently of the controller and coöperating with a notched ring to prevent backward movement of the controller from 65 the "off" or "running" position.
23. A starter for electric motors comprising fixed and movable contacts, the latter having "off", "starting", and "running" 70 positions, a pawl coöperating with a notched plate to accentuate the positions of the starter, and means for moving the pawl independently of the controller to allow forward movement of the controller from any position and backward movement thereof 75 from a "starting" position only.
24. In a controller, a rotatable drum, an operating handle therefor, and a pawl on said handle coöperating with a fixed ratchet plate to prevent backward movement of the 80 controller from certain positions.
25. In a controller, a rotatable drum, a pawl and ratchet coöperating to limit the movement of said drum from certain positions to one direction of rotation, and means 85 for moving said pawl independently of the drum.
26. In a controller, the combination of a stationary notched ring, a handle, and means mounted on the handle to interrupt the 90 movement of the handle at predetermined points on the notched ring and to allow only limited movement of the handle in a reverse direction.
27. In a controller, the combination of a 95 notched ring, a handle, and means mounted on the handle to interrupt the forward movement and to prevent a reverse movement of the handle at predetermined points on the notched ring.
28. In a controller the combination of a notched ring, a handle, and a latch engaging with the notched ring to interrupt the movement of the handle in one direction and to limit movements of the handle in the other direction at predetermined points on the notched ring.
- In testimony whereof I affix my signature, in the presence of two witnesses.
